UNITED STATES PATENT OFFICE.

RICHARD BORGELDT, OF METUCHEN, NEW JERSEY.

CIGAR-WRAPPER CUTTER.

953,941.

Specification of Letters Patent. Patented Apr. 5, 1910.

Application filed February 27, 1909. Serial No. 480,413.

To all whom it may concern:

Be it known that I, RICHARD BORGELDT, a citizen of the United States, and resident of Metuchen, Middlesex county, State of New Jersey, have invented certain new and useful Improvements in Cigar-Wrapper Cutters, of which the following is a specification.

My invention relates to devices for cutting cigar wrappers, and is intended for use in connection with the well-known perforated suction-box.

The object of my invention is to provide means enabling the same suction-box to be used for cutting wrappers of different sizes and shapes.

Two embodiments of my invention are shown in the accompanying drawings, in which—

20 Figure 1 is a plan view of a suction box, with my improved cutter applied thereto, a portion of the cutter being broken away; Fig. 2 is a vertical section on line 2—2 of Fig. 1; and Fig. 3 is a plan view showing another form of my invention.

The suction box A has a perforated top A' and is connected, as by means of a pipe B, with a suitable pump, fan, or other device for producing suction. On top of said 30 box is placed removably the cutting plate C, which has an opening C' of a shape corresponding to that of the wrapper to be cut, and a ridge C², preferably sharpened, is located at the edge of the opening, this ridge 35 forming a cutter against which the wrapper is pressed in the usual way by means of a roller drawn across the plate. The body of the plate, that is the portion surrounding the opening C', is imperforate and closes 40 or seals the perforations of the top A' which are covered by such body. Therefore, only those perforations which register with the opening C' are exposed, and suction is exerted through these openings to keep the 45 wrapper against the cutting ridge C². The suction exerted through the other perforations simply draws the plate C downward against the top A'. This suction and the weight of the plate will be sufficient to hold 50 it down firmly. The plate C is removable for instance by hinging it at C³ to the lugs A² of the suction box, each hinge pin or 55 pintle D being removable by pulling it out lengthwise, and a cotter pin E may be used to prevent accidental disengagement of the pintle.

When it is desired to cut a wrapper of a different size or shape, I withdraw the hinge pintles, remove the plate C, and substitute therefor another plate differing from it only 60 as regards the size or shape of the opening C'. Other constructions may be adopted to enable different plates to be placed on the top of the suction box table A.

In some cases, as illustrated in Fig. 3, I 65 might provide the plate c with an opening or cut-out portion c' and with a cutting ridge c² corresponding to one-half of the wrapper's outline, as it may be desired to leave a portion of the wrapper uncut.

The perforated top A' may be used as a table for placing the wrapper around the cigar in the well-known manner, the plate C (c) being swung aside or removed for 70 this purpose.

It will be understood that the perforations of the top A' extend over an area larger than the size of the largest opening C' for which the device is intended, but as shown in the drawing, it is superfluous to perforate 80 the entire top A'.

I claim as my invention:

1. The combination of a suction box provided with a top having a series of perforations, a plate arranged to be placed upon 85 said top and provided with an opening adapted to register with a plurality of said perforations at the same time, said plate being further provided with a cutting edge adjacent to said opening and having an imperforate portion located outside the opening and adapted to cover or seal a number 90 of the perforations of the top.

2. The combination of the suction box provided with a top having a series of perforations and a plate arranged to be placed upon said top and having an opening arranged to register with a plurality of said perforations at the same time, said plate being further provided with a cutting edge 100 adjacent to said opening and having an imperforate portion located outside the opening and adapted to cover or seal all the perforations of the top except those that register with said opening.

3. The combination of a suction box provided with a top having a series of perforations and a plate movable into and out of contact with the upper surface of said top, 110 said plate being provided with an opening arranged to register with a plurality of said perforations at the same time while the re-

mainder of said perforations are sealed by the plate and further having a cutting edge adjacent to said opening.

4. The combination of a suction box provided with a top having a series of perforations and a plate hinged to said box and movable into and out of contact with the upper surface of said top, said plate being provided with an opening arranged to register with a plurality of said perforations at the same time while the remainder of the said perforations are sealed by the plate and further having a cutting edge adjacent to said opening.
5. The combination of a suction box provided with a top having a series of perforations and a plate adapted to be placed upon said top, said plate being provided with an opening having the shape of the cut intended to be made in a cigar wrapper, the opening in said plate being arranged to register with a plurality of the perforations in the top at the same time while the remainder of said perforations are sealed by the plate.
6. The combination of a suction box provided with a top having a series of perforations and a plate hinged to said box and

movable into and out of contact with the upper surface of said top, said plate being provided with an opening having the shape of the cut intended to be made in a cigar wrapper, the opening in said plate being arranged to register with a plurality of the perforations at the top at the same time while the remainder of said perforations are sealed by the plate.

7. The combination of the suction box provided with a top having a series of perforations, with the plate mounted on said top to swing about a horizontal axis, said plate being provided with an opening arranged to register with a plurality of the perforations in said top, and further having a cutting edge adjacent to said opening and an imperforate portion located outside of the opening and sealing a number of the perforations of said top.

In testimony whereof I have hereunto set my hand in the presence of two subscribing witnesses.

RICHARD BORGFELDT.
